Application January 14, 1955, Serial No. 481,922

Claims priority, application Great Britain
January 18, 1954

1 Claim. (Cl. 89—34)

This invention relates to ammunition magazines for guns, of the kind in which an ammunition belt of interconnected rounds, usually formed by spring-metal clips pivotally interconnecting the rounds side-by-side in series, is stored in a box from which it is pulled by the feed mechanism of the gun.

The invention is applied to a magazine comprising a box having normally vertical separators dividing the box into open-topped cells for holding a belt of interconnected rounds festooned over the separators with a crest portion of the belt over the upper end of each separator and a loop portion of the belt in each cell. Each separator has, at its upper end, belt-engaging means to enter between successive rounds in the respective crest portion of the belt on the separator, so that each loop portion hangs independently in its cell, and the box has, at one end thereof, the usual outlet for withdrawal of the belt.

Previous magazines of the above kind have been designed for the belt to be withdrawn by all the rounds of each loop sliding in train over the curved upper end of the respective separator as the belt is withdrawn first from the cell nearest the outlet and then from the remaining cells in succession away from the outlet.

The object of the present invention is to provide an improved magazine wherein each crest portion of the belt is engaged so that the rounds forming the crest portion cannot slide in train over the separator but are guided to unwrap from the separator on withdrawal of the belt first from the cell furthest from the outlet and then from the remaining cells in succession towards the outlet.

According to the invention, the upper end of each separator has a belt-engaging means comprising a fixed, upwardly directed projection, to prevent rounds forming the respective crest portion of the belt from sliding in train either upwardly over the separator towards the outlet or laterally. At the upper end a guide means is also provided for unwrapping each respective crest portion from the projection, which defines an arcuate path extending first from the slide of the separator further from the outlet, then over the projection and finally in the direction of the outlet.

In a preferred construction, each separator has a head with an upwardly directed tooth forming the fixed projection and a sickle shaped arm forming the guide means and extending from the side of the head further from the outlet and arcuately upwardly and over the tooth to terminate with a free end directed towards the outlet.

A magazine as provided by the invention, ensures smooth withdrawal of the belt, the feed tension being transferred from one loop to the next without snatch, and jamming together of the last few rounds in each loop as they leave their cell is avoided.

Further, since ammunition in a magazine as provided by the present invention is held in place, by the independent suspension of each loop in its cell, until withdrawn for use, the magazine is particularly suitable for mounting on a gun so that the trunnion axis line passes

2

horizontally through the magazine approximately bisecting the loops at right angles with the result that at all times the ammunition in the magazine is disposed substantially equally on either side of the trunnion axis. Thus the centre of gravity of the magazine can initially be arranged to lie on and will move only along the trunnion axis as ammunition is used whereby the balance of the gun will not be affected. The magazines are particularly suitable for mounting at either side of a twin gun mounting.

The invention is illustrated by way of example on the accompanying drawing, in which:

Fig. 1 is a side elevation of a magazine as though on a gun, the nearer side wall being omitted to reveal the interior and, to preserve clarity of illustration, the actual mounting not being shown because it does not affect the invention.

Fig. 2 is a vertical cross-section on the line II—II of Fig. 1.

On a larger scale,

Fig. 3 is a fragmentary side elevation of the head of a separator, to show its shape, and

Figs. 4, 5 and 6 are a series of side elevations of the head of a separator and a portion of an ammunition belt thereon to show, in successive stages, the movement of the belt.

The magazine box 1 is shown in the drawing somewhat conventionally as a deep rectangular metal box, with a hinged top which can be opened for loading or 30 charging, and the box may have external mounting attachments.

The box 1 is located and supported on the mounting of a gun 2 so that it moves in elevation with the gun and the gun trunnion axis line T—T passes through the 35 box from end to end and through the centre of gravity of the box.

On the inside of each of the two side walls of the box 1 are provided vertical separator ribs 3, each rib on one 40 wall opposite a corresponding rib on the other wall, so that each two opposite ribs form a pair of ribs equivalent to a partition, whereby the box is in effect divided into cells.

An ammunition belt, of rounds 4 interconnected by spring metal clips 5 in a well-known manner, is arranged 45 in the magazine box by being festooned in loops hanging on the pairs of separator ribs 3, one loop to each cell between adjacent pairs of ribs 3.

From the end of the box further from the gun, the ammunition belt is led along the upper part of the box, 50 over a roller 6 at each side and through an outlet to a chute 7 to the gun feed and breech mechanism 8. During firing of the gun, the belt is pulled, round by round, by the feed mechanism which loads the gun and discards the clips 5 in the usual way. Thus the belt is used 55 up and the magazine emptied, cell by cell, from the further end of the box first.

Each separator rib 3 has a specially shaped head 9, see Fig. 3, which has a tooth 10, to engage between successive rounds 4 at the respective crest of the looped formation of the belt, and a sickle-shaped arm guide 11, to pass between the last two rounds of the respective loop of the belt and curve into the line of feed of the belt towards the rollers 6.

The teeth 10 prevent the crests of the belt from sliding in both directions over the tops of the separator ribs 3, so that each loop of the belt is suspended independently of the weight of the other loops.

At the top of each pair of separator ribs, the two guides 11, of the two respective heads 9, form supports for the cartridge bases and projectile noses of the rounds 70 as they are pulled out of the preceding cell.

As shown by Figs. 4 to 6, the guides 11 extend

between the last two rounds, 4^y and 4^z, of the respective loop and constrain the rounds forming the crest portion to follow an arcuate path so that the crest portion unwraps from the tooth 10. The guides 11 also serve, throughout the withdrawal of the respective loop, to guide all the rounds preceding the crest portion in an arcuate path smoothly from their cell into the lateral feed path towards the rollers 6, maintaining lateral separation of non-successive rounds, particularly in the final stages of the rising trough of each loop, and thus preventing jamming.

Further, the guides 11, by extending sufficiently along the feed path of the belt, suspend the succeeding loop, after the respective last round 4^z of the preceding loop and first round 4^x of the succeeding loop have left the teeth 10, until the feed tension of the belt has taken the weight of the succeeding loop. This avoids the crest of rounds between successive loops forming a slack bight in the belt as they leave the teeth 10 and which would cause snatch at the feed mechanism 8 as the weight of the next loop came suddenly on to the moving portion of the belt.

It will be noted from Fig. 1 that the pair of separator ribs 3 nearest the gun, beneath the rollers 6, are somewhat shorter than the others and do not have the guides 11. This is because the rounds leave the heads of these last separators in a substantially vertical direction without any appreciable lateral travel to the rollers 6 and therefore guides 11 are not required. Also, these last separators need not have the teeth 10 because they support only the tail of the belt and the belt is held against displacement in the magazine by the heads of the separators up to the last pair.

It will be noted that the magazine of the present invention has, apart from the exit rollers 6, no moving parts such as hinged partitions or feeding springs as in some previously proposed magazines of the vertical cell type. This absence of moving parts is of substantial practical advantage in obtaining consistent withdrawal of ammunition from magazines under widely varying service conditions and in enabling recharging of magazines to be effected simply and without requiring special inspection, testing or maintenance facilities.

The separator heads, by holding the ammunition belt in place as independently suspended loops and guiding and supporting its withdrawal from loop to loop, prevent unwanted displacement and insure proper withdrawal of the ammunition whatever the movement of the gun during firing. Magazines in accordance with the invention have proved satisfactory at all angles of fire between full vertical depression and full vertical elevation, i. e. from -90° to +90° from the horizontal.

In a general manner, while we have, in the above description, disclosed what we deem to be practical and efficient embodiments of our invention, it should be well understood that we do not wish to be limited thereto as there might be changes made in the arrangement, disposition and form of the parts without departing from the principle of the present invention as comprehended within the scope of the accompanying claim.

What we claim is:

A gun ammunition magazine comprising a box having normally vertical separators dividing the box into open-topped cells, an outlet for said box at one end thereof, the cells holding a belt of interconnected rounds extending from the outlet across the top of the box, the belt extending over the separator remote from the outlet first and then over successive separators, belt engaging means connected with the upper end of each separator, said belt engaging means comprising a fixed projection extending generally vertically as a continuation of the separator, said projection engaging between successive rounds to prevent the belt from sliding over the separator in either direction, and an arcuate guide member connected with said projection and spaced laterally therefrom, said guide member extending arcuately from a point beyond the end of that side of each separator further from the outlet, then over said projection and in the direction of said outlet whereby successive rounds pivot about each projection as the belt is drawn out over each separator and the belt is unwrapped from the crest portion of each separator.
